UNITED STATES PATENT OFFICE.

JOHN C. BRATTLY, OF ST. PAUL, MINNESOTA.

GUARD FOR GRAIN-BINDER CONVEYERS.

Application filed May 1, 1925. Serial No. 27,204.

To all whom it may concern:

Be it known that I, JOHN C. BRATTLY, a citizen of the United States, residing at St. Paul, in the county of Ramsey and State of Minnesota, have invented certain new and useful Improvements in Guards for Grain-Binder Conveyers, of which the following is a specification.

My invention relates to attachments for grain binders, and the object is to provide a guard over the front edge of the endless apron or conveyer that conveys the cut grain to the elevator of a binder. Said guard prevents wear and tear of the front edge of the conveyer and also prevents said edge and the ends of the cleats thereon from catching and tangling the grain especially when the grain is mixed with vines and weeds of various kinds as is often the case, and to save short grain from escaping from the machine.

In the accompanying drawing:

Fig. 1 is a perspective front view of the main portion of a binder with my attachment applied to it.

Fig. 2 is an enlarged section on the line 2-2 in Fig. 1.

Fig. 3 is a detail front view of my attachment removed from the binder.

Fig. 4 is the same as Fig. 3 only that it is designed to go on a binder having a right hand conveyer while that in Fig. 3 is for a binder having a left hand conveyer that is a conveyer on the left side of the driver.

Referring to the drawing by reference numerals, 5 designates the reel, 6 the elevator, 7-7^a the endless apron or conveyer moving the cut grain to the elevator. 8 and 8^a are the usual grain dividing or guiding devices at the front end of the machine, while 9 indicates the sickle bar having sickles 10 coacting with guards 11 to cut the grain. All of said parts are mounted in suitable framework only partly shown supported on the usual ground wheels like 12 and the bull wheel 13, from which latter operative motion is transmitted to all the working parts of the machine. The structure so far described is varied in some makes of binders but so general in all binders that I need not describe the same any further in detail.

I may state, however, as to Fig. 2 that the horizontal frame of the endless conveyer 7 is or may be considerably varied in construction; thus its front sill 14 may be

secured to the rear sill or connected with it by any suitable number and shape of cross bars 16, and longitudinal bolt rods (not shown), or in lieu of such rods it is common to use bars 17 in Fig. 2 having flattened angularly bent ends 18 secured to the sills 14 and 15 by bolts 19 and 20 respectively.

Each bolt 20, whether short or long, is always long enough outside the frame to receive a washer 21 and a nut 21^a.

My attachment consists of an angle bar preferably made of galvanized sheet iron and formed with a vertical flange 23 having a series of downwardly open notches 24 adapted to be slipped downwardly upon several of the bolts 20 and be held tightly, though removably, on the sill 14 by the washers 21 and nuts 21^a. The angle bar also has a horizontal flange 23^a projecting rearwardly upon the front edge of the conveyer 7 and the front ends of the cleats 7^a thereof (see Fig. 2). Said horizontal flange has at one end an extension 25 projecting upwardly and horizontally upon the lower portion of the lower member 6^a of the inclined elevator 6-6^a so as to prevent grain from dropping downwardly over the adjacent end of the endless conveyer 7.

In Fig. 3 24^a is a slotted hole to indicate that such holes may take the place of the notches 24. In Fig. 2 26 indicates a solid plate or board stiffening the frame 14-15-16.

While I have shown my invention as an attachment readily securable upon the usually existing bolts at the front of a binder conveyer, it will be understood that for binders not already having such bolts it is easy to furnish either bolts, lag-screws or cap screws for the purpose, and if my device is put on the binder at the factory it may be secured in place by rivets or any other suitable means.

As already stated, the device prevents tangling and clogging, and saves the front part of the conveyer from undue wear and it also aids in saving short grain by preventing its escape at the foot of the elevator.

What I claim is:

1. The combination with a grain binder having the usual platform frame and an endless conveyer and an inclined elevator arranged to receive the cut grain from the conveyer; said frame having a front sill, guard fingers projecting from the lower edge of the sill, an angle bar having a ver-

tical flange secured by bolts to the front side of the upper portion of the sill and a horizontal flange projecting loosely over the front edge of the conveyer apron.

5 2. The structure specified in claim 1, in which the elevator has an upper and a lower endless member and the horizontal flange of the angle bar has at one end an extension projecting upon the lower end of the lower member of the elevator.

10 3. The structure specified in claim 1, in which the angle bar has its vertical flange provided with clearances for the usual bolts extending through the front sill of the con-

veyer frame, and nuts on said bolts for 15 clamping the vertical flange to the front sill.

4. The structure specified in claim 1, in which the front edge or sill of the conveyer frame has a series of bolts and the vertical flange of the angle bar has downwardly open notches arranged to straddle said bolts, and means on the bolts for clamping the notched flange against the said front edge of the conveyer frame. 20

In testimony whereof I affix my signature.

JOHN C. X BRATTLY.
